FEATHER CUTTING HEAD

Earl A. Miller, Orem, Utah 84057

Filed Feb. 5, 1969, Ser. No. 15,647

Term of patent 14 years

Int. Cl. D8—02

U.S. Cl. D8—98

FIG. 1

FIG. 2

FIG. 3

FIG. 4

FIG. 5

FIG. 6

FIG. 7

FIG. 1 is a perspective view of such feather cutting head,

FIG. 2 is a front elevational view of a feather cutting head embodying my new design,

FIG. 3 is a side elevational view of such feather cutting head as viewed from the left,

FIG. 4 is a side elevational view of such feather cutting head as viewed from the right,

FIG. 5 is a rear elevational view of such feather cutting head,

FIG. 6 is a top plan view of such feather cutting head, and

FIG. 7 is a plan view of such feather cutting head as viewed from below.

The dominant features of the design are illustrated in solid lines.

I claim:

The ornamental design for a feather cutting head, as shown and described.
